UNITED STATES PATENT OFFICE

147,764

DESIGN FOR A SNACK TRAY

Thomas F. Sherbloom, Los Angeles, Calif.

Application May 14, 1946, Serial No. 129,687

Term of patent 14 years

(Cl. D44—10)

To all whom it may concern:

Be it known that I, Thomas F. Sherbloom, a citizen of the United States, residing at Los Angeles, in the county of Los Angeles and State of California, have invented a new, original, and ornamental Design for a Snack Tray, of which the following is a specification, reference being had to the accompanying drawing, forming part thereof.

The drawing illustrates a snack tray embodying my new design in which Fig. 1 is a perspective view; Fig. 2 is a side elevation view; Fig. 3 is a top plan view; and Fig. 4 is a fragmentary sectional view taken on line 4—4 of Fig. 2.

I claim:

The ornamental design for a snack tray, as shown.

THOMAS F. SHERBLOOM.
